UNITED STATES PATENT OFFICE.

JOHN P. MARTINKA, OF EL CAMPO, TEXAS.

BURGLAR ALARM.

Application filed September 25, 1926. Serial No. 137,659.

This invention relates to certain new and useful improvements in burglar alarms, and has more particular reference to burglar alarms of that type adapted to be associated with swinging closures, such as swinging doors of dwellings.

The primary object of the present invention is to provide an alarm of the above kind which is extremely simple and durable in construction as well as efficient in operation.

A more specific object of the invention is to provide a burglar alarm embodying a spring motor operated bell, and means rendered operable upon closing of a door and retention of the door in closed position, for preventing operation of the bell motor and sounding of the bell, and for releasing the bell motor upon subsequent opening of the door by an unauthorized person so as to cause sounding of the bell.

A more specific object is to provide an alarm of the above kind embodying a spring motor operated bell and means operable upon closing of a door for winding the motor of the bell and maintaining the motor wound and inoperative as long as the door is retained closed, said means being releasable upon subsequent opening of the door for permitting operation of the bell motor and sounding of the bell.

Other objects will become apparent as the nature of the invention is better understood, and the same consists in the novel form, combination and arrangement of parts hereinafter more fully described, shown in the accompanying drawing and claimed.

In the drawing, wherein like reference characters indicate corresponding parts throughout the several views,

Figure 1 is an elevational view of an alarm device constructed in accordance with the present invention and operatively associated with a swinging door;

Figure 2 is a view thereof partly in top plan and partly in section on line 2-2 of Figure 1;

Figure 3 is an enlarged elevational view of the spring motor operated bell forming a part of the alarm device shown in Figures 1 and 2; and

Figure 4 is an enlarged detail view partly in horizontal section, showing the door and the adjacent parts of the alarm operated and controlled thereby.

Referring more in detail to the drawing, the present invention embodies a spring

motor operated bell including a suitable frame preferably composed of a relatively large plate 5 having a pair of spaced sound producing shells 6 mounted upon the inner side of the upper portion thereof, and a second smaller plate 7 suitably rigidly connected to but spaced from and parallel with the lower portion of the plate 5. Supported by and mounted between the plates 5 and 7 is a conventional spring operated motor including a spring rotated drive shaft 8 and an escapement wheel 9 geared to and driven thereby in a manner well known in the art. This motor further includes a swinging or oscillatory escapement lever 10 operatively associated with the escapement wheel 9 and having its upper end connected by a link 11 with the intermediate portion of an oscillatory hammer 12 which is pivotally mounted at its lower end as at 13 and provided with a head 14 at its upper end disposed between and adapted to alternately strike the sound producing shells 6 when the hammer 12 is oscillated due to operation of the escapement lever 10 upon unwinding of the spring motor.

The spring motor further embodies a winding shaft 15 which is operatively connected to the drive shaft 8 for winding the motor spring, by means of a gearing including a relatively large segment gear 16 fixed upon the winding shaft 15.

A lever is provided for actuating or turning the segment gear 16 to cause winding of the motor spring, and this lever includes an inner section or arm 17 rigid with the gear 16 at a point intermediate the ends of the curved toothed edge of the same and depending as shown in Figure 3. The operating lever of gear 16 further includes an outer or lower section or arm 18 of U-shape cross section, the upper end portion of which embraces the upper or inner arm 17 and is pivoted to the lower end of the latter as at 19. It is thus apparent that the outer section 18 of the lever may be swung to various angular positions relative to the inner arm 17, and in order to maintain the arm 18 of the lever in any of such angularly adjusted positions, said arm 18 is provided with an arcuate series of transverse opening 20 adapted for selective reception of the laterally directed free ends of a spring arm 21 having one end suitably fixed to the segment gear 16. With the laterally directed end of the spring arm 21 inserted through one of the apertures 20

- and across the adjacent edge of the arm 17 as shown in Figure 3, the arm 18 will be prevented from swinging to the left of Figure 3 relative to arm 17. In a like manner, if 5 the spring arm 21 is disengaged and the lever arm 18 is swung to the right of Figure 3 until the uppermost opening 21 passes the left hand edge of arm 17, said spring arm 21 may be inserted in said uppermost opening 10 20 so as to contact the adjacent edge of arm 17 and maintain the arm 18 in such adjusted position relative to the arm 17. The purpose of this construction will presently become apparent.
- 15 Referring to Figures 1, 2 and 4, 22 indicates a door frame upon which is hung a conventional horizontally swinging and outwardly opening door 23. Slidably disposed and guided for limited movement through 20 the vertical stop strip 24 of the door frame 22 engaged by the free vertical edge portion of the door when closed, is a horizontal rod or plunger 25 whose inner end is arranged to engage the free end of one arm of a horizontally swinging bell crank lever 26 suitably mounted on the inside of the door frame 22 so that when the plunger 25 is forced inwardly said bell crank lever 26 is caused to exert a pull upon a pull rod 27 having one 25 end connected to the free end of the other arm of said bell crank lever as shown. The other end of pull rod 27 is pivotally connected to the free end of the arm 18 of the actuating lever for segment gear 16.
- 30 The plates 5 and 7 of the bell frame are provided with lateral flanges 28 so as to facilitate rigid mounting of the bell upon a wall within the dwelling equipped with the door 23, as indicated in Figs. 1 and 2.
- 35 For an understanding of the operation of the device, it is to be understood that the lever composed of arms 17 and 18 is adapted to be swung to the left of Figures 1 to 3 inclusive for effecting winding of the 40 motor spring. It is also to be understood that when the spring of the motor unwinds for actuating the hammer 12, the segment gear 16 will also be turned so as to cause return swinging movement of the lever composed of arms 17 and 18, to the right of said figures. Thus, with the device installed as 45 shown in Figures 1, 2 and 4, it will be seen that when the door 23 is closed it will engage the rod or plunger 25 and force the same inwardly so as to cause swinging of the bell crank lever 26 and thereby exert a pull upon rod 27 for turning segment gear 16 in the direction to wind the spring of the motor. As the rod 27 is of rigid form it is 50 apparent that movement thereof in the opposite direction will be prevented and as the gear 16 accordingly can not turn, the spring motor will be prevented from operating so as to retain the bell inoperative. However, as soon as the door 23 is opened, the 55 rod 25 will be released so as to allow movement of the rod 27 as caused by turning of the segment gear 16 under the influence of the spring motor. Thus, with the alarm set and the door thus surreptitiously opened, an 60 alarm will be sounded for warning the occupants of the dwelling. Naturally, the sounding of the alarm will only continue until the motor spring unwinds to return the parts to normal position with the plunger or rod 25 projected. It will also be apparent that by angularly adjusting the lever arm or section 18 relative to the section or arm 17, the distance of projection of the plunger or rod 25 upon full unwinding of the motor 65 spring may be varied so that the winding movement of segment gear 16 is accordingly varied and the subsequent length of time which the alarm is sounded may be accordingly changed. In some instances, it may be 70 desirable to have the alarm sound as long as possible in order that the alarm may be sure to be heeded. In other cases, however, it may be desirable to only have the alarm sound for a comparatively short interval, such as when the user is sure of being in the 75 vicinity of the alarm and does not desire any possibility of the burglar hearing the same when sounded. It will thus be apparent 80 that the adjustment of the arm sections 85 17 and 18 relatively, is of importance.
- 85 From the foregoing description it is believed that the construction and operation as well as the advantages of the present invention will be readily understood and appreciated by those skilled in the art.
- 90 Minor changes may be made without departing from the spirit and scope of the invention as claimed.
- 95 What I claim as new is:—
- 100 1. A burglar alarm comprising in combination, a spring motor, a bell operated thereby, said motor including a winding shaft, an operating lever for said shaft, a pull rod connected at one end to said lever, a bell 105 crank lever having one end connected to the other end of said pull rod, and a plunger projectable upon closing of a door by engagement of the door therewith for causing swinging of the bell crank lever and exerting a pull upon the pull rod for winding the spring motor of the bell, said plunger being releasable upon opening movement of the door for permitting unwinding of the 110 motor and sounding of the bell. 115
- 120 2. In a burglar alarm, the combination with a door frame having a stop strip, and a door mounted in the frame and engageable with said stop strip when closed, a plunger slidably mounted through said stop strip so as to be engageable and projectable by the door when closed, a spring motor operated bell, and an operative connection between the plunger and the motor of the bell for causing winding of said motor 125 130

upon closing of the door, said plunger being releasable upon opening movement of the door for permitting unwinding of the motor and sounding of the bell.

5 3. In a burglar alarm, the combination with a door frame having a stop strip, and a door mounted in the frame and engageable with said stop strip when closed, a plunger slidably mounted through said stop strip so as to be engageable and projectable by the door when closed, a spring motor operated bell, and an operative connection between the plunger and the motor of the bell

for causing winding of said motor upon closing of the door, said last named means 15 embodying a lever for operating the winding shaft of the bell motor composed of a pair of arms, one angularly adjustable relative to the other, for varying the distance of projection of the plunger, said plunger being releasable upon opening movement of the door for permitting unwinding of the motor and sounding of the bell. 20

In testimony whereof I affix my signature.

JOHN P. MARTINKA.
